UNITED STATES PATENT OFFICE.

FRED SIMPSON, OF BLUNDELLSANDS, NEAR LIVERPOOL, AND ARTHUR ROBERT THOMAS WOODS, OF HERTFORD, ENGLAND.

SHIP'S DAVIT.

Application filed September 3, 1921. Serial No. 498,441.

To all whom it may concern:

Be it known that we, FRED SIMPSON and ARTHUR ROBERT THOMAS WOODS, subjects of the King of Great Britain, residing, respectively, in Blundellsands, near Liverpool, in the county of Lancaster, England, and Hertford, England, have invented certain new and useful Improvements in and Relating to Ships' Davits, of which the following is a specification.

This invention relates to means for connecting together and for operating ships' davits, and is particularly to the type of gear described in the specification to British Letters Patent No. 113,625 granted to us, and the object is to simplify such gear by reducing the number of parts and space occupied and to provide a gear which shall be specially applicable to existing davits.

In our said specification we employ two pairs of linked segmental worm-wheels driven by a worm-shaft, there being one pair of worm-wheels for each davit; this construction necessitates one of the worm-wheel segments being mounted on each davit, and the provision of a horizontal worm-driving shaft extending from one davit to the other.

According to the present invention, instead of fitting a pair of linked worm-wheel segments to each davit, we employ a single pair only, of such linked segments disposed close together and driven by a short length of worm-shaft, this gear being located in a convenient position between the two davits.

The segments, their linkage and the worm or worms on the shaft are so arranged that on operating the shaft the co-ordinated movement which it is desired to impart to the davits is imparted in the first instance to the segments, the respective segments being connected to the davits by suitable gear, say drums and endless ropes or chains and engaging and disengaging gear, in such manner that the davits may be operated by the gear or be freed from the gear so as to be operated independently.

It has been proposed in the case of two drums respectively connected by endless ropes to collars fixed on the davits, to operate the drums by means of elliptic gears connected to the respective drums, or by means of linked mutilated pinions connected to the respective drums and operated by a driving pinion adapted to gear with one of the mutilated pinions and an intermediate

pinion driven by the driving pinion and adapted to gear with the other mutilated pinion.

In carrying out the present invention drums and endless chains or wire ropes are employed to transmit the motion of the worm-wheel segments, linked together and operated by a worm or worms, to two drums rotatably mounted on bearings fixed to the ship's structure independently of the davits; these bearings are usually hollow flanged bosses mounted so that the respective davits pass through the bores thereof concentrically but leaving sufficient clearance between the davits and the said bores to permit of the deflection of the davits relatively to the said bearings, so that the said drums have fixed centres of rotation which are not affected by davit deflection, in this way the latter deflection does not affect the tension of the rope or chain connecting the said drums to the worm wheel drums. The connection between the davit and the drum rotatably mounted in respect to the davit is made by means of engaging and disengaging gear fitted between a coupling part fixed to the davit and the independently mounted drum, said gear being preferably of the type described in the complete specification of our application for a Patent No. 20138 of 1919.

We prefer to connect the drums by means of wire rope, and the drums are double-grooved and have a central clamping groove running from the one groove to the other in which central groove the rope is securely attached to the drum by clamping bolts.

Usually the short worm-driving shaft is arranged so that in plan its axis cuts the line joining the centres of the segmental worm-wheels at a point between these centres, and preferably the said axis may be inclined to the said line at right angles, in which case a single worm suffices for both worm-wheels.

The operating gear is positive in the sense that each davit is under control throughout the whole of its movement and the co-ordinated movement between the davits is effected independently of any guy-rope connection between the two davit heads.

The invention is illustrated in the accompanying drawings in which:

Fig. 1 is a plan view of the general arrangement of the gear.

Fig. 2 is a plan view to a larger scale.

of the linked worm gear, the davit operating drums and the davits.

Figs. 3 to 6 are diagrammatic views to a smaller scale than Fig. 2, showing the position of the gear at different points in the movement.

Fig. 7 is a view similar to Fig. 2 and shows a modification.

Figs. 8, 9, 10 and 11 are detail views of the davit operating drums with the rope fastening gear, the coupling members, and the engaging and disengaging gear.

Fig. 8 is a plan view; Fig. 9 an elevation in section on the line IX, IX of Fig. 8; Fig. 10 an outside elevation on a plane of projection normal to the arrow Z; and Fig. 11 a fragmentary section on the line XI, XI of Fig. 8.

Referring first to Figs. 1 to 6 and 8 to 11, which illustrate the preferred form, A and B are respectively, say, the fore-and-aft davits, and C and D are the fore-and-aft worm-wheel segments. These segments are mounted on discs c^1 and d^1 and may initially be angularly adjustable on the said discs so that the same gear may be made to suit different arrangements of davits; the discs c^1 and d^1 are rotatably mounted on vertical studs c^2 and d^2 carried from a bed-plate E and the discs are provided with crank pins c^3 and d^3 which crank pins are connected together by a connecting rod F.

Between the two segments, and adapted to engage with either of both of them is a worm-wheel G carried on a worm shaft g^1 mounted in bearings g^2 carried from the bed-plate E and fitted with suitable thrust bearings, one end of the shaft G is fitted with the universal coupling g^3 , one of the elements of the coupling having a shaft g^4 which extends to an operating pillar g^5 (see Fig. 1) where it is connected by a second universal coupling g^6 to a shaft mounted in this pillar and operated through suitable gear and handles g^7 .

c^4 and d^4 are fixed limiting stops against which the respective ends of the connecting rod F engage (see right hand end Fig. 2) in extreme in-board and out-board positions of the gear. On the under-side, and attached to the discs or formed integral therewith are rope-drums H^1 the construction of which is similar to the davit operating rope-drums H to be subsequently described.

K are coupling members rigidly attached to the respective davits, H are the davit operating rope-drums, one for each davit; these rope-drums are rotatably mounted on the bosses of hollow bearings h^1 secured by flanges h^2 to the structure of the ship, say by means of an attachment plate.

The drums are provided with gun-metal bushes h^4 . The bore of the bearing is concentric with the davit but is substantially

larger in diameter than the davit so that deflection of the latter does not affect the bearing of the rope-drums and therefore has no effect on the tension of the ropes connecting the rope-drums H and H' together.

Each rope-drum H has two normal grooves, an upper groove h^5 and a lower groove h^6 , and at one part of the circumference these two grooves are joined by a centre groove h^7 with oblique ends (see Figs. 8 to 11); the rope is led on to the normal portion of the upper groove h^5 , it then passes somewhat more than half way round this groove, then through the centre groove h^7 into the lower groove h^6 , passing somewhat more than half way round this groove and then off the drum. The portion of the rope in the centre groove h^7 is clamped to the drum by the clamping bolts h^8 ; thus in addition to the wrapping friction between the rope and the rope drum, the rope is positively attached to the drum by means which permit of its adjustment.

The coupling members K consist of semi-circular lugs caused to grip the davit by tightening bolts k^1 and a pinching screw k^2 , and the straight portions of the lugs are carried beyond the bolts k^1 so as to form jaws k^3 to take the connecting and disconnecting gear next to be described.

Each of the davit operating rope-drums H is provided with two pairs of lugs h^9 in each of which a bell-crank tumbler h^{10} is pivoted on a pin h^{11} . When the tumblers are each turned into the position shown in full lines in Fig. 9, their engaging parts engage with the respectively opposite jaws k^3 of the coupling members K, and they thus connect the davit operating rope-drums non-rotationally with the respective davits through the couplings K; the connection is such as to couple these parts in definite angular relationship whilst permitting a certain freedom of transverse movement of the davit due to deflection when the latter is loaded.

When each of the tumblers is turned into the position shown in chain dotted lines on the right hand side of Fig. 9, it will be seen that the davit is left quite free from the davit operating rope-drum, so that in the event of the gear becoming deranged the davits may be left practically free to be operated individually in the usual manner. Each tumbler is fitted with a locking pin h^{12} which is adapted, by engagement with the top of the lugs h^9 to hold the tumbler in engagement as shown in full lines in Fig. 9, or, by engagement of the sides of the lugs to hold the tumbler out of engagement when in the position shown in chain-dotted lines on the right hand side of Fig. 9. In order to ensure that the coupling K can be fixed to the drum H in the one angular position only, the engaging parts of the tumbler may

be so shaped that each will enter one only of the engaging jaws h^3 ; lubrication between the rope-drum H and its bearing h^1 is effected by a Stauffer lubricator fitted to the 5 boss h^{13} .

As stated, each of the discs c^1 and d^1 of the respective worm-segments C and D is fitted with a rope-drum H' bolted thereto or integral therewith; and each of these drums 10 has grooves corresponding with the upper groove h^5 , the lower groove h^6 and the centre groove h^7 described in connection with the drum H , and the centre grooves of the drum H' are fitted with clamping bolts similar to 15 the bolts h^8 described in connection with the drum H , so that the connecting rope R is positively attached to a davit drum H and to a segment drum H' as shown; the rope passing from an upper groove in H' to an upper 20 groove in H , then passing somewhat more than half round this groove, then through the centre groove into the lower groove, then somewhat more than half round this groove, to the lower groove in H' , then somewhat 25 more than half way round this groove, then through the centre groove in H' into the upper groove, and somewhat more than half way round this groove, then to the drum H .

The angular extent of the grooves h^5 and 30 h^6 is such as to permit the necessary angular movement of drums without the rope leaving these grooves.

The action is as follows:—

Referring to Figs. 2 to 6;

Assuming c and d to be the centres of motion of the worm segments, it will be seen that the linkage connecting these together is the arm $c\ c^3$, the rod F , the length of which is c^3 35 and the arm $d\ d^3$. In Fig. 2 the davits A and B are in their in-board position, and it will be seen that the davit arms are in this 40 position practically parallel respectively with the arms $c\ c^3$ and $d\ d^3$ and that the worm segment D is in gear with the worm G, the segment C being free. When the gear is 45 operated by the handle g^7 the worm is rotated and moves the segment D into the position shown in Fig. 3 where the rod F and the arm $d\ d^3$ are in line, the davit A having been 50 moved by the linkage into its extreme position to the left with the davit head at a^1 , whilst the head of the davit B is at b^1 . Continued movement of the operating gear moves the segment D into the position shown 55 in Fig. 4, the rod F is now practically normal to the two crank arms, the head of the davit A has been moved back to the position a^2 and the head of the davit B has been moved to b^2 ; the segment C and segment D 60 are in this position both in engagement with the worm G; further movement of the operating handle causes the worm to engage with segment C leaving the segment D free and this latter segment is moved by the linkage 65 into the position shown in Fig. 5 where

the arm $c\ c^3$ is in line with the rod F , the davit heads being moved into the positions a^3 and b^3 shown.

Further movement of the gear moves the segment C into the position shown in Fig. 6, in which the head of the davit A has been moved forward to its out-board position a^4 and the head of the davit B drawn back to its in-board position b^4 , it will be noted that in this position as well as in each intermediate position the davit arms are practically parallel with the respective arms $c\ c^3$ and $d\ d^3$.

By the operation of the handle g^7 in the reverse direction the davit heads are moved 80 back to the in-board position.

It will be seen that the engagement of the heads of the respective ends of the rod F with the respective limit stops c^4 and d^4 definitely limits the movement of the gear 85 at the end of the out-board and in-board movements respectively.

It will also be seen that the co-ordinated movements of the davit arms are those necessary in launching the boat, and that each 90 davit is positively and mechanically held under control by the operating gear throughout its co-ordinated movement.

In the arrangement described the two segments are brought sufficiently near together 95 to enable them to gear with the one worm.

In some cases it may not be possible to do this, and in these cases the modification shown in Fig. 7 is provided. In this modification there are two worms G^1 and G^2 ; 100 these are mounted on a worm shaft g^8 , carried in end bearings g^9 , with a centre thrust bearing g^{10} , these bearings being mounted on a bed-plate E^1 , the shaft being provided with, say, a squared part g^{11} to which a handle is fitted by which the gear is operated. In other respects the gear is constructed and operates in the manner above described. In Fig. 7 the ropes are shown 105 as being fitted with turn-buckles M comprising right and left handed screws, and a connecting sleeve nut, and these may be used to take up any slack rope.

These turn-buckles may be fitted to the arrangements first described. In some cases a spring buffer (not shown) may also be fitted to each length of rope, and these may also be fitted to the arrangement first described.

Each of the arrangements described is 110 specially suitable for application to existing davits. The central portion comprising the bed-plate E , the segments and their operating gear may be fitted in any convenient position, and the operating shaft g^4 may be carried to an operating pillar g^5 located in a position best adapted for manipulating the gear.

The details of construction may be varied to suit different arrangements.

Having now fully described our invention, we declare that what we claim and desire to secure by Letters Patent is:—

1. A device of the character described, including a pair of davits, a rotatable member secured to each davit, means to rotate said members, including two spaced apart worm wheel segments, a connecting rod pivotally mounted on each segment and joining the same, and a single rotatable member engageable by each segment for rotating said segments.
2. The device of claim 1, said single rotatable member engaging said segments alternately.
3. The device of claim 1, said single rotatable member having its axis of rotation at

right angles to the axes of rotation of said segments.

4. The device of claim 1, said single rotatable member including a worm.

In testimony whereof we affix our signatures in presence of two witnesses.

FRED SIMPSON.
